MUFFLER WITH PLURAL SIDE BRANCH CHAMBERS

Howard R. Johnson, Pound, Va.

Application May 2, 1950, Serial No. 159,413

8 Claims. (Cl. 181—48)

1

This invention relates generally to sound mufflers or silencers particularly of the type suitable for use with the exhaust system of an internal combustion engine and has for its principal object the provision of a simpler and more efficient muffler.

It is a primary object of the invention to provide a light weight muffler of simple construction which will be highly effective as a silencer but which will minimize to a surprising degree the objectionable back pressure on the motor.

A still further object of the invention is to provide a silencer in which the exhaust gases are divided into two parts so that each one of the two parts can flow thru aligned openings.

In the drawings:

Figure 1 is a central axial section.

Figure 2 is a plan view of a washer.

Figure 3 is a transverse section thru the muffler with the partition in place but omitting the baffles.

Figure 4 is an elevation of the central strip.

In the drawings the numeral 10 is a cylindrical pipe of normal size and length for the purpose having at its front end the head 11, having an inlet opening 12 surrounded by a nipple 14, a suitable size is about 5" in diameter and about three quarters of a yard long.

The central strip 15 is a metal sheet the length of the muffler and fitting snugly from top to bottom but having a plurality of notches 16 in its top edge. The central partition 15 divides the interior of the pipe 10 into two equal spaces 17 and 18 preferably unrestricted.

Within the pipe 10 I mount a plurality of washers or baffles 20 each fitting fairly snugly within the pipe and having a central slot 21 to receive the dividing sheet 15 and having on each side of the slot an opening 23 and 24 each shaped as shown in the drawings and preferably having an area equal to the area of the entrance opening 12. It will be noted that the holes are all of the same size and by virtue of the slot and notch connections all of the holes 23 are aligned and all of the holes 24 are aligned. The inner curve 25 of the two openings together form a circular baffle 26 and the proximate edges 27 of the openings 23 or 24 are spaced appreciably from the dividing partition or strip so that the openings 23 and 24 are roughly centrally positioned in the passageway 17 and 18.

In order to achieve the greatest amount of reduction of sound I find it highly advantageous to space the baffles 20 so as to form the chambers, such as 30, 31, 32, 33 and 34, in constantly de-

2

creasing axial lengths. I prefer that the initial chamber 30 shall be greater than the diameter of the pipe, the second chamber 31 approximately the diameter of the pipe, the third chamber 32 about half the diameter of the pipe, and the axial lengths of the next two chambers 33 and 34 should be reduced consecutively by a half inch. The net result of this is that the muffler can be used under different conditions and with different engines and will silence all of these whereas if the baffles 20 were equally spaced the result would be far less efficient. I also find that by increasing the axial length of chamber 35 over that of 34 and again increasing the axial length of the next chamber 36, superior results are obtained and in the preferred model I add a chamber 37 of very short axial length and follow this with a chamber 38 which is only a trifle shorter than the axial length of chamber 36. The ratio of the chambers beginning at the inlet end will be 12:10:5:4:3:4:8:2:7.

For ease in manufacturing I prefer to have the strip 15 and the various transverse baffles or disks 20 formed as a unit and it is also my preference to weld the washers to the strip before insertion in the tube. Sometimes I weld the unit lightly or crimp the end of the tube 10 to insure against rattling and yet have the unit removable with very little trouble.

The muffler under test runs remarkably cool and the back pressure is considerably less than 2" of mercury at 50 miles per hour. As an example of the efficiency of the device, a standard car was driven up a hill and it slowed down to 15 miles per hour at the top when using its own muffler. On using the muffler of the present invention, however, the car was still going 28 miles per hour as it crossed the top.

What I claim is:

1. A muffler including a cylindrical casing with a restricted inlet opening, a flat partition strip longitudinally dividing the casing into two equal portions, and a plurality of transverse baffles substantially closing the casing and forming chambers, each baffle having therethru a pair of openings of equal area, one in each longitudinal portion, the baffles being secured to the partition strip so the strip and the baffles may be removed as a unit from the casing.

2. The muffler of claim 1 in which the strip is notched, the baffles are disks each having a central slot to receive the strip and to be held in the notches, and the openings are spaced from the strip and from the casing.

3. A muffler including a casing having a re-

stricted inlet opening, a flat partition strip longitudinally dividing the casing into two equal portions, and a plurality of transverse baffles closing the casing and forming chambers, each baffle having therethru a pair of openings, one in each longitudinal portion, the several openings on each side of the strip being aligned.

4. The device of claim 3 in which the area of each of the openings is equal to the area of the inlet.

5. The muffler of claim 3 in which the axial lengths of the chambers formed by the baffles decrease in regular order from the inlet end to a midpoint and then increase in axial length.

6. The muffler of claim 1 in which there are at least eight baffles spaced to form chambers of at least seven different axial lengths.

7. The muffler of claim 1 in which the axial

length of the chamber between the inlet and the first baffle is more than one sixth of the length of the shell and the ratios of the successive chambers is 12:10:5:4:3.

8. A muffler having a series of at least six transverse perforated baffles forming chambers of different axial lengths, the final chambers having the ratio 4:8:2:7, the diameter of the muffler at the same scale being approximately 10.
